UNITED STATES PATENT OFFICE.

STEFAN KISS V. ECSEGHY, OF VIENNA, AUSTRIA-HUNGARY, ASSIGNOR OF SIXTY-FIVE ONE-HUNDREDTHS TO THE FIRM OF HANDELSGESELLSCHAFT KLEINBERG & CO., OF VIENNA, AUSTRIA-HUNGARY.

AIMING DEVICE FOR ORDNANCE.

No. 853,007.

Specification of Letters Patent.

Patented May 7, 1907.

Application filed February 24, 1906. Serial No. 302,764.

To all whom it may concern:

Be it known that I, STEFAN KISS VON ECSEGHY, a subject of the King of Hungary, residing at Vienna, Empire of Austria, have invented certain new and useful Improvements in Aiming Devices for Ordnance; and I do hereby declare the following to be a full, clear, and exact description of the invention, such as will enable others skilled in the art to which it appertains to make and use the same.

My invention relates to aiming devices which may also be used as automatic electric firing devices for guns and being more particularly designed for guns on board ship.

In my improved device two points are brought to coincidence or into contact with each other at the moment when, owing to the training of the gun and the ship's motions the plane of the trajectory of the projectile goes exactly through the target and the inclination of the gun to the horizontal plane by the elevating gear and the motion of the ship corresponds exactly to the distance of the gun from the target (the range)—and to the position of the target relatively to the horizon.

In the annexed drawing Figures 1 to 3 illustrate by way of example one method of carrying into practice my invention, Fig. 1 is a side elevation, partly in section, Fig. 2 a front view and Fig. 3 a plan view of a gun provided with my aiming device, Figs. 4, 4^a and 5 show in vertical section plan and elevation respectively a correction device to be used in connection with my invention, Figs. 6, 7 and 8 show in side elevation, front elevation and inverted plan view a safety device to be used in connection with an automatic electric firing device constructed in accordance with my invention, Figs. 9, 10 and 11 are similar views of another safety device for the same purpose. Fig. 12 shows one form of electric firing device adapted for use with the invention.

Referring now particularly to Figs. 1 to 3, 2 indicates a sighting device of any known or preferred construction, such as a telescope which is free to turn round a point 1 in the geometrical axis of a bar or shaft 5 carried by the gun barrel or a part, (such as the cradle), movable longitudinally relatively to the gun barrel but prevented from turning round the same, so that the sighting device may be per-

manently directed upon the target independently of any movements whatever of the ship and the gun.

An arm 3 is secured to the sighting device 2. For facilitating the explanation of my invention it is assumed for a moment that the point 4 at the free end of this arm 3 is exactly in line with the optical axis of the sighting device as is indicated in dotted lines in Fig. 1 so that when the sighting device is directed upon the target the point 4 is exactly in the vertical plane passing through the target and the optical axis of the sighting device. With this plane the plane of the trajectory of the projectile to be fired from the gun must exactly coincide in order that the projectile may hit the target, the horizontal distance between the optical axis of the sighting device and the axis of the bore of the gun, as well as any lateral deviation of the projectile resulting from any cause whatever, being neglected. The sighting device is moreover so held that the said vertical plane passes through the point 1, called hereinafter the main pivot point.

6 is a frame free to turn around the geometrical axis of the said bar or shaft 5 passing through the main pivot point and permanently parallel to the axis of the bore of the gun. This frame is provided with an arm 7 and is permanently held in a vertical plane by weights or otherwise so that the point 8 at the free end of the arm 7 is permanently held in the vertical plane passing through the axis 5. This plane is again neglecting the horizontal distance between the axis 5 and the axis of the bore of the gun and any lateral deviation of the projectile, the plane of the trajectory of the projectile to be fired from the gun and its line of intersection with the vertical plane passing through the sighting line, that is to say the optical axis of the sighting device directed upon the target is the vertical line through the main pivot point 1. If now the point 8 enters the latter vertical plane the plane of the trajectory of the projectile coincides exactly with this vertical plane and the gun is correctly trained horizontally.

The arm 7 is adjustable in the frame 6 along an arc of a circle having the main pivot point 1 for its center according to the distance between the target and the gun the same as the usual breech or rear sight of guns.

The distance between its point 8 and the main pivot 1 is the same as that between the latter and the point 4 of the arm 3, and the shape and size of the arm 7 are so chosen that when its point 8 enters the vertical plane passing through the sighting line and when it is properly adjusted in accordance with the distance between target and gun and when the angle between the sighting line and the axis 5 (which is the same as the angle between the sighting line and the axis of the bore of the gun) corresponds to such range the point 8 is in coincidence or in contact with the point 4. After having adjusted the arm 7 in the frame 6 according to the range previously determined, it is only necessary to hold the sighting device directed exactly upon the target and the sighting line in a vertical plane passing through the main pivot point 1 and to hold the frame 6 also in a vertical plane whatever may be the motions of the ship and the gun, and to train the gun and adjust its elevation until the point 8 comes into contact or coincides with the point 4. At this moment as will be seen from the above explanation the plane of the trajectory of the projectile to be fired from the gun coincides with the vertical plane passing through the sighting line and the angle between the sighting line and the axis of the bore of the gun (or the axis 5) corresponds exactly to the range, so that when the gun is fired at this moment the projectile is sure to hit the target irrespective of the position of the target relative to the horizon and irrespective of any oscillations of the ship and the gun. The firing of the gun in this moment may be effected either on command or automatically by means of an electric circuit closed by the two points 4 and 8 making contact with each other as is indicated in Fig. 1.

The condition that the vertical plane through the sighting line shall pass through the main pivot point 1, may be fulfilled by making the sighting device capable of turning round a spindle 9 the axis of which passes through the main pivot point 1; such spindle 9 being capable of turning round the axis 5 and another axis 10 at right angles to both axes 5 and 9 and by arrangements for permanently holding the same vertically by means of weights or by hand or otherwise; a convenient means for holding vertically the axis 9 consists in attaching to the axis 5 an elastic saddle 37 similar to a bicycle saddle on which the gun pointer is seated who by maintaining his equilibrium notwithstanding any oscillatory motion of the ship, such as rolling, will hold vertically the axis 9 and also the frame 6 secured to the axis 5.

It is not necessary that the point 4 shall be exactly in line with the optical axis of the sighting device that is to say in the sighting line, it may be placed out of this line pro-

vided that the point 8 of the arm 7 is shifted in the same direction and to the same extent horizontally and vertically. Moreover it is not necessary that the axis 9 and the transverse axis 10 pass through the main pivot point 1; the transverse axis 10 may be carried by a bar turning round the axis 5, the axis 9 turning round the axis 10 provided that the said bar and the axis 9 are always held in a vertical plane passing through the sighting line. In this case the points 4 and 8 must be the same distance from the transverse axis 10 and the main pivot point 1 will be the point of intersection of the axes 5 and 9. 80

The arm 7 may be adjusted in accordance with the range in the following manner. This arm is carried by a bar 11 curved on the arc of a circle, the center of which is the main pivot point 1 or the transverse axis 10, the bar 11 being guided in the correspondingly curved frame 6. This bar 11 is polygonal (triangular or quadrangular) in transverse section and is provided at its edges with parts of a male screw thread into which engages a nut 12 provided with a hand wheel 13 journaled in the frame 6 but prevented from moving longitudinally therein, such arrangement allowing of adjustment, but the bar 11 may be adjusted by any other suitable means. 95

The corrections for any lateral deviation of the projectile as well as for the direction and speed of the onward movement of the target and the ship carrying the gun are obtained as in the usual rear sights by laterally adjusting the arm 7. For this purpose the arm 7 is secured to a slide 14 (see also Figs. 4, 4^a and 5) movable along a plate 15 fastened to the bar 11 such slide 14 being operated by a stud 16 working in a slot in the slide as shown more clearly in Fig. 4^a and adjustable in accordance with the speed of the target in a grooved block 18, which is adjusted by means of a worm and worm wheel in accordance with the direction of the onward movement of the target until an arrow 17 fastened on the stud 16 is parallel to such direction. The shaft of the worm wheel 19 is adjustable along a grooved block 20 so allowing for the strength of the wind and this block is adjusted by turning the same by means of a worm and worm wheel allowing for the direction of the wind. The shaft of the wheel 21 is adjustable along a grooved block 22 which allows for the speed of the ship carrying the gun and this block is secured to a shaft 23 turned from the training gear of the gun in such a manner that the groove in this block is always parallel to the keel of the ship. This shaft 23 is automatically turned by the training gear through the ball and socket joint 40, rod 41, telescoping with the rod 42, ball and socket joint 43, shaft 44, and pinion 45 meshing in the circular rack 46 which rotates with the gun carriage. In this way all the corrections 125 130 135 140 145 150

required are imparted to the slide 15 independently of one another so allowing the arm 7 to be adjusted by the entire amount of correction. This total correction when adjusted for a given position of the gun will be changed when the training of the gun is changed so as to remain accurate for all positions of the gun provided that the speed and the direction of the movement of the target, the wind and the ship carrying the gun are not changed. In lieu of or besides the correction device just described any other correction devices may be used.

In case of sudden oscillations of the ship it may happen that the axis 9 and the frame 6 come out of the true vertical position; the points 4 and 8 might then come into contact with each other while the gun is not accurately trained and in case of automatic electric firing the gun would be fired, but the projectile would miss the target. In order to avoid this the axis 9 is extended downward beyond the main pivot point 1 and to its lower end a casing 24 (see also Figs. 6, 7 and 8) is attached carrying a plate 25 upon which a ball 26 rests freely between four pendulums 27 suspended at the top of the casing in the corners of a square, at the lower ends of the pendulums 27 and below the plate 25 contact piece 28 are secured in such a manner that when the axis 9 is exactly vertical in which case the plate 25 is exactly horizontal, each contact piece is in contact with that diagonally opposite thereto. The contact piece of two pendulums at two adjacent corners of the square are electrically connected with each other and the contact pieces of the pendulums at the other corners of the square one is connected with the point 4 and the other with the point 8 a suitable source of electricity serving for the purpose of firing the gun being included in one of these circuits. Now when the axis 9 comes out of the vertical and consequently the plate 25 comes out of the horizontal position at least one of the pendulums 27 will be swung out which action will be assisted by the ball 26 rolling on the plate 25 while the pendulum diagonally opposite to the first named will be arrested by the plate 25; therefore the contact between at least two contact pieces 28 and consequently also the firing circuit will be broken, whereby the firing of the gun is prevented when the axis 9 is not exactly vertical even if the points 4 and 8 are in contact with each other.

The axis 9 is normally vertical, the plate 25 horizontal and the contact pieces 28 are in contact with each other so that under normal conditions the gun can be fired electrically only when the sighting device is directed upon a point of the horizon, but if the target is not in the horizon the axis 9 is no more exactly vertical when the sighting device is directed upon the target and consequently in

this case the firing circuit would be interrupted as the contact of at least two diagonally opposite contact pieces would be broken and it would be impossible to fire the gun electrically. In order to avoid this objection and to enable the gun to be fired electrically even if the target is not in the horizon the dependent frame is not rigidly secured to the axis 9 but is pivoted to the said axis and is adjustable relatively thereto by any suitable means (such as a worm wheel and worm 29 and 30 respectively, see Fig. 6). By these means the casing 24 may be adjusted in accordance with the range and the height of the target in such a manner that the plate 25 is exactly horizontal and the pendulums 27 are in contact position when the axis 9 is in the vertical plane passing through the line of sight and the sighting device is directed exactly upon the target. A very fine adjustment of the casing 24 is not required; for instance a readjustment of this casing is not necessary when with one and the same target the range varies within rather wide limits.

At the lower end of the bar 11 there is attached a casing 31 (see also Figs. 9, 10, 11) provided with a plate 32 and two pendulums 35, 35 and which casing is adjusted in accordance with the range and the height of the target in such a manner that the plate 32 is exactly horizontal and the pendulums 35, 35 hang exactly vertical touching this plate, and contact pieces 36, 36 at the lower end of such pendulums are in contact with each other, when the axis 5 is in the vertical plane passing through the line of sight and is inclined to this line of sight at an angle corresponding to the range and the height of the target, that is to say at the correct elevation angle. The contact pieces are included in the firing circuit being in series with the contact pieces 28 and the points 4 and 8. When therefore the axis 5 is not in the proper direction or is thrown out of this direction owing to a sudden movement of the ship one of the pendulums 35 will be swung out whereby the contact pieces 36, 36 will be separated and thus the firing circuit broken. This action is assisted by two balls 33, 34 freely resting on the plate 32 and separated by a web in the casing 31, one or the other of these balls roll toward the outer edge of the plate and pushes outward the pendulum adjacent thereto whenever the plate 32 is not exactly horizontal.

It will be seen that the casing 31 has to be adjusted to the desired elevation of range, and the gun can only be fired when it is at such elevation, and at no other time. When the range is changed, then, of course, the casing 31 has to be re-adjusted to correspond. This adjustment may be effected in any desired way, as by turning the casing on its pivot in the bar 11 and then locking it in position.

Fig. 12 shows a convenient form of firing device, which may be used in the apparatus, but is not of itself a part of the invention. This firing device comprises a primer 40 secured in and insulated from the metallic bottom of the cartridge shell 41 provided with an inwardly projecting point 42. Opposite this point there is provided in the cartridge another point 43 electrically connected to the cartridge shell.

44 is a firing pin mounted in and insulated from the breech block 45. One terminal of a source of electricity is connected to the firing pin, and the other to the breech block; the contacts 4, 8, 36, 36, 27, 27, and 28 are included in series in the electric circuit. When the firing pin 44 is in the firing position, as shown in Fig. 12, the spark will cross the gap between the points 42 and 43, and the cartridge will be fired.

Claims

1. In aiming devices for ordnance the combination with the ordnance, a bar, means for holding the geometrical axis of such bar permanently parallel to the axis of the bore of the ordnance, a frame adapted to turn around the geometrical axis of such bar whereby such frame can be held in a vertical plane passing through the geometrical axis of such bar, a point carried by such frame, means for adjusting such point in accordance with the desired elevation of the ordnance, means for adjusting such point in accordance with any desired lateral corrections, a sighting device adapted to swing freely in all directions around a point of the geometrical axis of the said bar whereby such sighting device may be permanently held directed to the target with the vertical plane passing through the optical axis of such sighting device also passing through the said point in the geometrical axis of the said bar and an arm rigidly secured to the sighting device the free end of such arm being adapted to coincide with the point on the said frame whereby such coincidence will take place when the gun is trained and elevated in accordance with the position of the target relatively to its distance from such gun, substantially as and for the purpose described.

2. In aiming devices for ordnance, the combination with the ordnance, a bar, means for holding the geometrical axis of such bar permanently parallel to the axis of the bore of the ordnance, a frame adapted to turn around the geometrical axis of such bar whereby such frame can be held in a vertical plane passing through the geometrical axis of such bar, a point carried by such frame, means for adjusting such point in accordance with the desired elevation of the ordnance, means for adjusting such point in accordance with any desired lateral corrections, a sighting device adapted to turn freely around an axis such axis being at right angles to its op-

tical axis and adapted to turn around two other axes at right angles to each other one of the latter axes being the geometrical axis of the said bar and the other being at right angles to the last named axis and the said axis at right angles to the optical axis of the sighting device whereby such sighting device may be permanently held directed to the target with the vertical plane passing through the optical axis of such sighting device also passing through the said point in the geometrical axis of the said bar and an arm rigidly secured to the sighting device, the free end of such arm being adapted to coincide with the point on the said frame whereby such coincidence will take place when the gun is trained and elevated in accordance with the position of the target relatively to its distance from such gun, substantially as and for the purpose described.

3. In aiming devices for ordnance, the combination with the ordnance, a bar, means for holding the geometrical axis of such bar permanently parallel to the axis of the bore of the ordnance, a frame adapted to turn around the geometrical axis of such bar whereby such frame can be held in a vertical plane passing through the geometrical axis of such bar, a point carried by such frame, means for adjusting such point in accordance with the desired elevation of the ordnance, means for adjusting such point in accordance with any desired lateral corrections, a sighting device adapted to swing freely in all directions around a point of the geometrical axis of the said bar, an attendant's saddle connected to the said bar in proximity to the sighting device whereby the attendant is enabled to take hold of the sighting device and whereby such sighting device may be permanently held directed to the target with the vertical plane passing through the optical axis of such sighting device also passing through the said point in the geometrical axis of the said bar and an arm rigidly secured to the sighting device the free end of such arm being adapted to coincide with the point on the said frame whereby such coincidence will take place when the gun is trained and elevated in accordance with the position of the target, relatively to its distance from such gun, substantially as and for the purpose described.

4. In aiming devices for ordnance, the combination with the ordnance, a bar, means for holding the geometrical axis of such bar permanently parallel to the axis of the bore of the ordnance, a frame adapted to turn around the geometrical axis of such bar whereby such frame can be held in a vertical plane passing through the geometrical axis of such bar, such frame comprising a bar curved to the arc of a circle and polygonal in transverse section, a correspondingly curved guide for such curved bar such guide being

revolubly attached to the bar parallel to the axis of the bore of the ordnance, means for moving such bar along the guide, a point carried by such curved-bar, means for adjusting such point in accordance with any desired lateral corrections a sighting device adapted to turn freely around an axis such axis being at right angles to the optical axis of the sighting device and adapted to turn around two other axes at right angles to each other, one of the latter axes being the geometrical axis of the bar parallel to the bore of the ordnance and the other passing through the center of curvature of the said curved bar and being at right angles to the last named axis and the said axis at right angles to the optical axis of the sighting device whereby such sighting device may be permanently held directed to the target with the vertical plane passing through the optical axis of such sighting device also passing through the said point in the geometrical axis of the said bar and an arm rigidly secured to the sighting device the free end of such arm being adapted to coincide with the point on the said frame whereby such coincidence will take place when the gun is trained and elevated in accordance with the position of the target relatively to its distance from such gun, substantially as and for the purpose described.

5. In aiming devices for ordnance, the combination with the ordnance, a bar, means for holding the geometrical axis of such bar permanently parallel to the axis of the bore of the ordnance, a frame adapted to turn around the geometrical axis of such bar whereby such frame can be held in a vertical plane passing through the geometrical axis of such bar, such frame comprising a bar curved to the arc of a circle and polygonal in transverse section, a correspondingly curved guide for such curved bar such guide being revolubly attached to the bar parallel to the axis of the bore of the ordnance, a nut adapted to turn in such guide and to engage screw thread segments cut into the edges of such curved bar, means for preventing such nut from moving longitudinally, a point carried by such curved bar, means for adjusting such point in accordance with any desired lateral corrections, a sighting device adapted to turn freely around an axis such axis being at right angles to the optical axis of the sighting device and adapted to turn around two axes at right angles to each other, one of the latter axes being the geometrical axis of the bar parallel to the bore of the ordnance and the other passing through the center of curvature of the said curved bar and being at right angles to the last named axis and the said axis at right angles to the optical axis of the sighting device whereby such sighting device may be permanently held direct to the target with the vertical plane passing

through the optical axis of such sighting device also passing through the said point in the geometrical axis of the said bar and an arm rigidly secured to the sighting device the free end of such arm being adapted to coincide with the point on the said frame whereby such coincidence will take place when the gun is trained and elevated in accordance with the position of the target relatively to its distance from such gun, substantially as and for the purpose described.

6. In a combined aiming and automatic electric firing device for ordnance the combination with the ordnance of a bar means for holding the geometrical axis of such bar permanently parallel to the axis of the bore of the ordnance a frame adapted to turn around the geometrical axis of such bar whereby such frame can be held in a vertical plane passing through the geometrical axis of such bar, a point carried by such frame, means for adjusting such point in accordance with the desired elevation of the ordnance, means for adjusting such point in accordance with any desired lateral corrections, a sighting device adapted to swing freely in all directions around a point of the geometrical axis of said bar whereby such sighting device may be permanently held directed to the target with the vertical plane passing through the optical axis of such sighting device also passing through the said point in the geometrical axis of the said bar, an arm rigidly secured to the sighting device the free end of such arm being adapted to make electric contact with the point on the said frame whereby such contact will be made when the gun is trained and elevated in accordance with the position of the target relatively and its distances from the target and an electric circuit adapted to be closed by such contact and including in series connection a source of electricity and an electric firing device, substantially as and for the purpose described.

7. In a combined aiming and automatic electric firing device for ordnance, the combination with the ordnance of a bar means for holding the geometrical axis of such bar permanently parallel to the axis of the bore of the ordnance, a frame adapted to turn around the geometrical axis of such bar whereby such frame can be held in a vertical plane passing through the geometrical axis of such bar, a point carried by such frame, means for adjusting such point in accordance with the desired elevation of the ordnance, means for adjusting such point in accordance with any desired lateral corrections, a sighting device adapted to swing freely in all directions around the point of the geometrical axis of said bar whereby such sighting device may be permanently held directed to the target with the vertical plane passing through the optical axis of such sighting device also

passing through the said point in the geometrical axis of the said bar an arm rigidly secured to the sighting device the free end of such arm being adapted to make electric contact with the point on the said frame whereby such contact will be made when the ordnance is trained and elevated in accordance with the position of the target relatively and its distances from the target and an electric circuit adapted to be closed by such contact and including in series connection a source of electricity and an electric firing device, a casing adjustably connected to the point carried by the frame adapted to turn around the geometrical axis of the bar parallel to the axis of the bore of the gun, a plate mounted in such casing, a ball or balls freely resting on such plate, pendulums suspended in such casing and carrying contact pieces and means for connecting such contact pieces in series with the electric firing device, substantially as and for the purpose described.

8. In a combined aiming and automatic electric firing device for ordnance the combination with the ordnance of a bar, means for holding the geometrical axis of such bar permanently parallel to the axis of the bore of the ordnance, a frame adapted to turn around the geometrical axis of such bar whereby such frame can be held in a vertical plane passing through the geometrical axis of such bar, a point carried by such frame, means for adjusting such point in accordance with the desired elevation of the ordnance, means for adjusting such point in accordance with any desired lateral corrections, a sighting device adapted to turn freely around an axis, such axis being at right angles to its optical axis and adapted to turn around two other axes at right angles to each other one of the latter axis being the geometrical axis of the said bar and the other being at right angles to the last named axis and the said axis at right angles to the optical axis of the sighting device, an arm rigidly secured to the sighting device, the free end of such an arm being adapted to make electric contact with the point on the said frame whereby such contact will be made when the ordnance is trained and elevated in accordance with the position of the target relatively and its distance from the target and an electric circuit adapted to be closed by such contact and including in series connection a source of electricity and an electric firing device, a casing adjustably connected to the axis of the sighting device at right angles to its optical axis, a plate mounted in such casing, a ball or balls freely resting on such plate, pendulums suspended in such casing and carrying contact pieces and means for connecting such contact pieces in series with the electric firing device, a casing adjustably connected to the point carried by the frame adapted to carry around the geometrical axis of the bar parallel to the axis of the bore of the gun, a plate mounted in such last named casing, a ball or balls freely resting at such plate, pendulums suspended in such casing and carrying contact pieces and means for connecting such contact pieces in series with the electric firing device, substantially as and for the purpose described.

50 9. In a combined aiming and automatic electric firing device for ordnance, a combination with the ordnance of a bar means for holding the geometrical axis of such bar, permanently parallel to the axis of the bore of the ordnance a frame adapted to turn around the geometrical axis of such bar whereby such frame can be held in a vertical plane passing through the geometrical axis of such bar, a point carried by such frame, means for adjusting such point in accordance with the desired elevation of the ordnance, means for adjusting such point in accordance with any desired lateral corrections, such means comprising a series of cranks, one for each movement for which correction has to be made,

nation with the ordnance of the bar, means for holding the geometrical axis of such bar permanently parallel to the axis of the bore of the ordnance, a frame adapted to turn around the geometrical axis of such bar whereby such frame can be held in a vertical plane passing through the geometrical axis of such bar, the point carried by such frame, means for adjusting such point in accordance with the desired elevation of the ordnance, means for adjusting such point in accordance with any desired lateral corrections, a sighting device adapted to turn freely around an axis, such axis being at right angles to its optical axis and adapted to turn around two other axes at right angles to each other one of the latter axis being the geometrical axis of the said bar and the other being at right angles to the last named axis and the said axis at right angles to the optical axis of the sighting device, an arm rigidly secured to the sighting device, the free end of such an arm being adapted to make electric contact with the point on the said frame whereby such contact will be made when the ordnance is trained and elevated in accordance with the position of the target relatively and its distance from the target and an electric circuit adapted to be closed by such contact and including in series connection a source of electricity and an electric firing device, a casing adjustably connected to the axis of the sighting device at right angles to its optical axis, a plate mounted in such casing, a ball or balls freely resting on such plate, pendulums suspended in such casing and carrying contact pieces and means for connecting such contact pieces in series with the electric firing device, a casing adjustably connected to the point carried by the frame adapted to carry around the geometrical axis of the bar parallel to the axis of the bore of the gun, a plate mounted in such last named casing, a ball or balls freely resting at such plate, pendulums suspended in such casing and carrying contact pieces and means for connecting such contact pieces in series with the electric firing device, substantially as and for the purpose described.

10. In a combined aiming and automatic electric firing device for ordnance, the combination with the ordnance of a bar means for holding the geometrical axis of such bar, permanently parallel to the axis of the bore of the ordnance a frame adapted to turn around the geometrical axis of such bar whereby such frame can be held in a vertical plane passing through the geometrical axis of such bar, a point carried by such frame, means for adjusting such point in accordance with the desired elevation of the ordnance, means for adjusting such point in accordance with any desired lateral corrections, such means comprising a series of cranks, one for each movement for which correction has to be made,

65 9. In a combined aiming and automatic electric firing device for ordnance, a combi-

the crank pin of one crank constituting the crank axis of the next following crank means for adjusting such cranks according to the speed and to the direction of the corresponding movement, means for coupling the first crank axis of the series with the training gear of the gun, a sighting device adapted to swing freely in all directions around a point of the geometrical axis of the said bar whereby such sighting device may be permanently held directed to the target with the vertical plane passing through the optical axis of such sighting device also passing through the said point in the geometrical axis of the said bar

and an arm rigidly secured to the sighting device the free end of such arm being adapted to coincide with the point on the said frame whereby such coincidence will take place when the gun is trained and elevated in accordance with the position of the target relatively to its distance from such gun, substantially as and for the purpose described.

In testimony whereof, I affix my signature, in presence of two witnesses.

STEFAN KISS V. ECSEGHY.
